AIRPLANE TOW TARGET

Alan E. Brickman, New Haven, Conn., assignor
to The American Steel and Wire Company of
New Jersey, a corporation of New Jersey

Application June 21, 1943, Serial No. 491,711

4 Claims. (Cl. 273—105.3)

This invention relates to airplane tow targets and particularly to an improved removable insert member for the lead cable ring thereof.

In an airplane tow target, it is the usual practice to provide a length of wire tow cable having a relatively heavy tow target release member or mechanism attached to its free end which is lowered from the plane while in flight. The release member consists generally of a longitudinally extending body portion, which is usually cylindrical in shape with a cone-shaped portion arranged on the inner end thereof or that end which is attached to the wire tow cable. There is also provided a relatively short lead cable having a sleeve target attached to one end thereof which is adapted to be towed by the plane, and a ring member pivotally attached to a connection or terminal arranged on the opposite end of the lead cable. After the tow cable has been dropped from the plane with the release member floating freely in the atmosphere, the short lead cable is then dropped from the plane together with the sleeve target attached thereto with the ring member or the lead cable passing along the tow cable. The forward travel of the plane draws the tow cable through the lead cable ring at a terrific rate of speed and as the ring member approaches the body portion of the release member, the ring passes thereover and catches on an outwardly projecting finger-like release member carried by the body portion so as to prevent the passing of the release mechanism all the way through the ring member. The target is then in position on the end of the tow cable and ready for gunnery practice.

Such an arrangement is unsatisfactory for the reason that oftentimes, the ring member in passing along the tow cable shears the same at a point immediately next to the cone-shaped portion of the body portion of the release member due to the speed at which the tow cable passes through the ring member and the weight of the release mechanism. This condition results in the loss of the release mechanism which is hazardous to persons on the ground and may result in terminating the flight thereby involving considerable expense and loss of time.

Accordingly, it is the general object of the present invention to insure that the ring of the lead cable of a tow target is properly guided to and passes over the inner end of the release mechanism without shearing the tow cable so as to eliminate the foregoing disadvantages.

It is a more specific object of this invention to provide an improved removable insert member for

the ring of the lead cable of a tow target having a limited opening arranged therethrough through which the tow cable passes so as to guide the ring to position opposite the inner end of the release mechanism with the insert member adapted to be forced from the position in the ring upon striking the inner end of the body portion of the release mechanism.

It is another object of this invention to provide an insert member for the ring of the lead cable of a tow target which is simple and inexpensive in its construction, and, at the same time, efficient and effective in its use.

Various other objects and advantages of this invention will be more apparent in the course of the following specification and will be particularly pointed out in the appended claims.

In the accompanying drawing there is shown, for the purpose of illustration, an embodiment 20 which my invention may assume in practice.

In the drawing:

Figure 1 is a side elevational view of the outer end of an airplane tow target cable showing the improved insert member of my invention incorporated with the ring of the lead cable of the tow target;

Figure 2 is a side elevational view similar to Figure 1 showing more in detail the tow target release mechanism and the position the tow target assumes thereon when in use;

Figure 3 is a front elevational view of one of the halves of the improved insert member of my invention showing how it is assembled in position into ring of the lead cable of the tow target; and

Figure 4 is a sectional view taken on line IV—IV of Figure 3.

Referring more particularly to the drawing, there is shown in Figures 1 and 2 thereof, the lower end of a wire tow cable 2 having a relatively heavy tow target release mechanism 3 arranged on one end thereof. The release mechanism 3 consists generally of a longitudinally extending cylindrical body member having a cone-shaped portion 4 arranged on the inner end thereof to which one end of the tow cable 2 is attached. Intermediate the length of the body portion of the release mechanism, there is arranged in a longitudinally extending groove 5 therein, a release member 6 which is pivotally attached to the body member, as at 7. On the outer end of the release member 6, there is arranged a hook or finger-like member 8 which extends through the body member and outwardly to one side thereof. At the front end of the groove 5 in the body member, there is arranged a trigger 9 which is pivot-

ally attached to the body member, as at 10, and cooperates with the release member 6 to move the same about its pivotal connection 7 so as to move the finger-like member or hook 8 into the body member for a purpose hereinafter to be described.

There is adapted to be attached to the release mechanism 6, a relatively short target lead cable 12 having a terminal connection 13 arranged on one end thereof to which a suitable sleeve target (not shown) is attached. On the other end of the lead cable 12, there is arranged preferably a terminal eye connection 14 having a slotted hole 15 disposed therein. There is arranged through the slotted hole 15, preferably a swivel member 16 which is pivotally attached to a target lead cable or traveler ring 17, as at 18. It will be understood that both the tow cable 2 and the target lead cable 12, as shown in the drawing, are disposed substantially in the position they assume when they are dropped from the airplane and are towed through the air thereby.

According to the present invention, as shown in Figures 3 and 4 of the drawing, there is provided a pair of complementary substantially U-shaped members 19 for insertion into the target lead cable ring 17. Each of the members 19 is preferably made from resilient sheet metal and the leg portions 20 thereof are preferably arcuated both laterally and longitudinally thereof, and there is arranged in each of the legs centrally thereof, a groove 21. The bottom side of each of the insert members 19 is substantially flat and there is arranged centrally of the flat bottom surface, a semi-cylindrical groove 22 which extends substantially perpendicular to the legs 20 and the grooves 21 therein. There is struck up from the flat bottom surface of each of the members 19, centrally thereof preferably an outwardly extending lug portion 23 which is disposed to one side of the semi-cylindrical portion 22 therein. On the opposite side of the semi-cylindrical portion 22 of each of the members 19, there is arranged a hole 24.

The two complementary insert members 19 are positioned in the target lead cable ring 17 in the following manner. These members 19 are placed together so that the flat bottom surfaces thereof are superimposed relative to each other with the lug portion 23 of one of the members positioned in the hole 24 of the other member so that the two members are maintained in alignment with each other. By arranging the two members 19 in such a manner, it will be seen that there is provided through the center thereof, a cylindrical hole due to the cooperation of the two semi-cylindrical portions 22 of these members. The two complementary members, as an assembly, are now ready to be positioned within the lead cable ring 17. They are held together and are forced into the lead cable ring, and it will be seen that the inner periphery of the ring will ride over the outer edge portion 25 of the leg portions 20 which edge portions are smaller in diameter than the inner diameter of the ring, thereby compressing the outer ends of the leg portions. After the assembly has been moved into the lead cable ring so that the groove 21 in each of the members 19 is positioned directly opposite the inner periphery of the ring, it will be seen that the leg portions 20 are moved outwardly due to the resiliency thereof and that the inner periphery of the lead ring 17 will then be disposed in the grooves 21 of each of the complementary insert members 19, and that the insert members

are held in position therein primarily due to the resiliency of the leg portions thereof.

The target lead cable 12, together with the sleeve target, and the lead cable ring 17, together with the two complementary members 19 arranged therein, is now ready for use and adapted to be positioned on the release mechanism 3 for gunnery practice. It will be understood that the hole arranged through the insert members 19 formed by the cooperation of the semi-cylindrical portions 22 carried thereby, is slightly larger than the diameter of the tow cable 2. The upper end of the tow cable 2 is then threaded through the hole formed by the insert members and is dropped from the plane. As the plane moves along, it will be seen that the lead cable ring 17, together with the insert member assembly arranged therein, passes along the cable due to the speed of the plane until the lead cable ring 17 approaches the conical-shaped portion 4 of the body portion of the release mechanism 3. It will be seen that the insert members 19 will strike the conical-shaped portion 4 of the release mechanism with a terrific force thereby springing the leg portions 20 of both of the insert members 19, so as to force them from position in the lead ring 17. When the insert members 19 are forced from position in the lead ring 17, it will be seen that the lead ring is centered over the upper end of the conical-shaped portion 4 of the release mechanism, and upon further movement of the lead cable ring 17, it will pass over the conical portion 4 and back over the release mechanism until it strikes the finger-like member or hook 8 extending outwardly from the body portion of the release mechanism. This target lead cable, with the sleeve target carried thereby, is then towed through the air by the plane and is then in position on the end of the tow cable ready for gunnery practice.

After the desired amount of gunnery practice has been had with this target, a new target is dropped from the plane and the lead cable ring 17 thereof passes along the tow cable 2 in the same manner as has been described. The insert members 19 of the lead cable ring 17 of this new target are forced from their position in the lead ring in the same manner as the first target ring upon striking the upper end of the conical-shaped portions 4 of the release mechanism 3. As the lead cable ring of this new target passes over the conical-shaped portion 4 and back over the body portion of the release mechanism, it will be seen that it strikes the trigger 9 which, in turn, moves the release member 6 about its pivotal connection 7 so as to move the finger-like member or hook 8 into the body of the release mechanism. Upon movement of the finger-like member or hook 8 into the body member, it will be seen that the lead cable of the first target passes over the outer end of the release mechanism and falls to the ground. Other new targets are positioned on the lower end of the tow cable in a similar manner. It will be understood that both of the insert members 19, when forced from the lead ring 17, fall to the ground and are used, unless recovered, for positioning only one target on the end of the tow cable.

As a result of my invention, it will be seen that the tow cable 2 is centered within the lead cable ring 17 when the lead cable ring reaches the inner end of the release mechanism 3. By providing such an arrangement, it will be seen that the release mechanism passes freely into and through the lead ring thereby preventing contact of the

tow cable 2 with the lead ring 17 at the inner end of the release mechanism 3, so as to eliminate the danger of shearing the tow cable 2 at this point.

While I have shown and described a specific embodiment of my invention, it will be understood that this embodiment is merely for the purpose of illustration and description and that various other forms may be devised within the scope of my invention, as defined in the appended claims.

I claim:

1. An insert for the lead cable ring of a tow target of the class described, comprising two complementary substantially U-shaped halves with the leg portions of each of said halves being resilient and bent inwardly toward each other and being arcuate-shaped, each of said leg portions having a groove arranged therein centrally and longitudinally thereof, the bottom of each of said halves being substantially flat and superimposed relative to each other and having a semi-cylindrical portion arranged centrally of the flat bottom surface thereof whereby a cylindrical hole is arranged through the insert member axially thereof when the two halves are assembled together with the diameter of said hole being slightly larger than that of the tow cable with which the insert member is adapted to be used, the outer diameter of the assembled halves being slightly larger than the inner diameter of the lead cable ring, with the diameter of the insert member at the bottom of the grooves in said leg portions being substantially equal to the inner diameter of said lead cable ring, said insert member due to the resiliency of the leg portions adapted to be forced into said lead cable ring and held yieldably therein with the inner circumference of said lead cable ring disposed in the grooves of said leg portions.

2. A lead cable ring for guiding an airplane target and the like along a tow cable and onto an elongated release member which comprises, an annular member having an inside diameter

slightly larger than the outside diameter of said release member, guide means resiliently held in said annular member and shaped to provide a central opening slightly larger than said tow cable, said guide means being constructed and arranged to guide said ring along said cable and onto said release member and means whereby said guide means may be removed from said annular member by contact with said release member.

3. A lead cable ring for guiding an airplane target and the like along a tow cable and onto an elongated release member which comprises, an annular member having an inside diameter larger than the outside diameter of said release member, guide means in said annular member comprising two members having spring biased arms resiliently engaging said annular member, said members being shaped to provide a central opening slightly larger than said tow cable, said guide means being constructed and arranged to guide said ring along said cable and onto said release member and means whereby said guide means may be removed from said annular member by contact with said release member.

4. A lead cable ring for guiding an airplane target and the like along a tow cable and onto a cylindrical release member having a tapered portion at the entry end thereof which comprises, an annular member having an inside diameter slightly larger than the outside diameter of said release member, guide means in said annular member comprising at least two members having spring biased arms resiliently engaging said annular member, said members shaped to provide a central opening slightly larger than said tow cable, whereby said guide means is adapted to guide said ring along said cable and onto said release member and means whereby said guide means may be removed from said annular member by contact with the tapered end of said release member.

ALAN E. BRICKMAN.
